[57] CLAIM

The ornamental design for a handle with sidearm for a diagnostic urinometer unit, as shown.

DESCRIPTION

FIG. 1 is a perspective view of a handle with sidearm for a diagnostic urinometer unit showing our new design.

FIG. 2 is a front elevational view of the handle.

FIG. 3 is a rear elevational view of the handle.

FIG. 4 is a top plan view of the handle.

FIG. 5 is a bottom plan view of the handle.

FIG. 6 is a left side elevational view of the handle.

FIG. 7 is a right side elevational view of the handle.

FIG. 1.

FIG. 2.

FIG. 3.

FIG. 4.

FIG. 5.

FIG. 6.

FIG. 7.
